Atty.

UNITED STATES PATENT OFFICE.

WALTER P. GISSKE, OF CHICAGO, ILLINOIS.

ELECTRICAL CONNECTER.

Application filed June 2, 1922. Serial No. 585,439.

My invention relates to electrical connectors, and more particularly to a resilient means for connecting a conductor to a terminal, such for example, as a spark plug terminal.

It is a purpose of the invention to provide means for readily connecting a conductor to the terminal by resilient means so that a good electrical connection is provided which can be made without the use of any tools, or without unscrewing any parts, or screwing any parts together. Preferably the connector comprises the resilient member having substantially parallel end portions connected by an intermediate bowed portion, one of said end portions being provided with an opening for receiving a member on the other end portion, said member being preferably provided with a head adapted to pass through said opening, and with an abutment between which and said end portion a conducting member may be clamped. The terminal is preferably so made that it will receive a conductor having a terminal thereon that is made in the form of a loop or eye, but if so desired, the connector may be so made that it will receive an ordinary straight conductor, such as a wire. The resilient member may be made of sheet metal or of spring wire, and may be secured to a spark plug by means of a nut having a head thereon, which nut is threaded on the ordinary threaded upper end portion of the central contact member of the spark plug, or the central contact of the spark plug may be made with a head and an abutment thereon for receiving said resilient member. The connecting member will, however, not be limited in its use to spark plugs, or similar articles, but may be provided with a wood screw or any other suitable means for detachably mounting the same on a support of either insulating or conducting material.

It is a particular purpose of the invention to provide a resilient connector which is easily moved into and out of connecting position. In order to provide a device that is easily operated, the end portion, having the opening through which the head is adapted to be passed, is provided with a slot or opening that has a wide portion and a narrow portion, thus forming an opening of the shape of a key-hole slot, and the member for receiving the conductor is preferably nor-

mally aligned with the narrow portion of the slot whereby the head on said member will prevent disconnection of the conductor receiving member and the said end of the resilient clip. Upon movement of the said end portion of the clip or connector in an upward direction and in a direction transversely of the conductor receiving member, the enlarged or widened portion of the opening is adapted to be aligned with the head of the member so as to permit the ready removal of the end of the resilient clip from the headed member. It will be seen that by such movement, the head will readily pass through the wider portion of the opening, but unless both an upward and transverse movement takes place the head will not be aligned with the widened portion of the opening, thus preventing disengagement of the terminal on the conductor from the connector by an upward movement thereof.

Other objects and advantages of the invention will appear as the description of the accompanying drawings proceeds. However, I desire to have it distinctly understood that I do not intend to limit myself to the exact details shown or described, but that I intend to include as part of my invention all such obvious changes and modifications of parts as would occur to a person skilled in this art and as would fall within the scope of the claims.

In the drawings:

Fig. 1 is a top plan view showing my improved electrical connector mounted on a spark plug;

Fig. 2 is a side elevation thereof;

Fig. 3 is a side elevation of the headed nut;

Fig. 4 is a view similar to Fig. 1 of a modified form of the device;

Fig. 5 is a side elevation of the form shown in Fig. 4, partly broken away;

Fig. 6 is a fragmentary sectional view of said form of the device;

Fig. 7 is a perspective view of a spring clip made of spring wire;

Fig. 8 is a sectional view of a further modified form of the device; and

Fig. 9 is a top plan view of the clip shown in Fig. 1.

Referring in detail to the drawings, in Figs. 1 and 2 is shown a spark plug 11 having the central contact 12 upon the upper end of

which is mounted the headed nut 13, said nut 13 having screwthreaded engagement with the outer end portion of said central contact. The nut 13 is provided with a narrowing neck portion 14 and a head 15, and is adapted to clamp the resilient connection clip 16 between itself and the shoulder 17 on the upper end portion of the spark plug, the end portion 18 of the member 16 being 10 provided with a suitable opening through which the central contact of said spark plug passes. The clip 16 is also provided with an intermediate bowed resilient portion 19 and with an end portion 20 which extends 15 substantially parallel to the end 18, and which is provided with an opening 21 therein, which has a widened portion of a somewhat larger diameter than the head 15, and a narrow end portion 22, which is of a 20 smaller diameter than the head 15, said head 15 being normally aligned with the narrow portion 22 of the slot so that the same engages the member 20 adjacent the narrow portion with the reduced neck 14 extending 25 through the same.

The member 20 is provided with the finger piece 23 whereby the same may be pressed upwardly and laterally due to the bowed portion 19 therein, so as to cause the head 30 15 to align with the large part of the opening in the member 21 to permit removal of the end 20 from the headed member or nut 13. Preferably a conductor 24 having a terminal member 25 thereon, which is provided with a suitable enlarged end portion 26 having the substantially circular opening 27 therein, is connected with the connecting member and with the spark plug by placing the enlarged end 26 over the headed member 35 13 with the headed member extending through the opening 27 between the head 15 and the enlarged portion of the nut 13 which serves as an abutment for said member.

In the form shown in Figs. 4 to 6 inclusive, the spark plug 11' is provided with a central contact member 12' which has a circular enlargement or abutment 28 thereon, a reduced portion 29 and a head 30. The clip 16' having the intermediate bowed resilient portion 19' and the end portion 20' having an opening similar to that in the member 19, is mounted on said central contact 12'. The inner end portion 18' of the member 16' extends closely adjacent the end portion 20' thereof, and is provided with a downwardly struck recess at 31 in which the abutment 28 is adapted to seat. Thus, when a conductor 24 having the terminal 25 thereon, which is provided with an end portion 35 26 as previously described, is placed on the member 29 between the head and the abutment 28, the end portion 26 thereof will be clamped between the members 20' and 18' and will establish a good electrical connection, the members being readily disconnected

by actuation of the spring clip by means of the finger piece 23', similar to the finger piece 23, in Figs. 1 to 3 inclusive.

In Fig. 7 is shown a connector 32 which is made of spring wire, and which has the end loop 33 thereon at one end, which is adapted to occupy the position of the end portion 18 or 18', previously described, and with a body portion comprising parallel strands of wire having the offset portions 34 75 and 35 therein connected by the straight portions 36 to form an elongated loop, the opposite end of the member being provided with laterally offset portions 37 bent so as to form an opening that has an enlarged portion 38 and a reduced portion 39, so as to operate in the same manner as the key-hole opening in the clip 16 or 16', said wire being offset from the plane of the loop 37, so as to form the finger piece 40 which operates in the same manner as the finger piece 23 to disengage the spring clip from the central contact of the spark plug, or other similar device.

In Fig. 8, an electrical connector 41 is shown comprising the end portions 42 and 43 connected by the elongated upwardly extending resilient loop 44, the member 42 being provided with a key-hole slot 45 and a finger piece 46 similar to what is shown in Figs. 1 95 to 5 inclusive, and the member 43 being provided with a downwardly struck portion 47 forming a recess for receiving the abutment 48 on the wood screw or similar member 49 having the reduced portion 50 between 100 said abutment 48 and the head 51.

It will be understood that any form of fastening means can be used for securing the connector to any suitable base, and that the wood screw 49 is shown merely for purpose of illustration.

Having thus described my invention, what I desire to claim and secure by U. S. Letters Patent is:

1. An electrical connector comprising a 110 resilient clip having a free end portion and a headed member mounted thereon, the free end portion of said clip having an opening therein aligning with said headed member, said member extending through said opening with the head thereon normally engaging with the edge of said clip at said opening to detachably hold the free end portion of said clip in engagement with said head.

2. An electrical connector, comprising a 120 resilient clip having substantially parallel end portions, and an intermediate bowed portion connecting said end portions, one of said end portions having an opening therein and the other end portion having means projecting therefrom through said opening into yielding interlocking engagement with the edge of the opening in said first end portion, said projecting means being provided with an abutment and receiving a connecting ter- 130

rnal, said first mentioned end portion clamping said terminal between itself and said abutment on said projecting means.

3. An electrical connector, comprising a headed member and a bowed resilient clip associated therewith having an opening having a wide portion and a narrow portion, said narrow portion normally aligning with said headed member, the head on said member extending through said opening and the edge of said clip at said narrow portion of said opening normally resiliently engaging said head to hold said clip in engagement with said head.

15 4. An electrical connector, comprising a resilient clip having substantially parallel end portions, and an intermediate bowed portion connecting said end portions, one of said end portions having an opening therein 20 and the other end portion having a stud projecting therefrom, said stud having an enlarged head adapted to be projected through said opening and be held interlocked therewith by the resilient action of said clip, and 25 having an abutment, said stud being adapted to receive a connecting terminal, said first mentioned end portion clamping said terminal between itself and said abutment when said head is engaged with said end portion.

30 5. An electrical connector, comprising a resilient clip having substantially parallel end portions, and an intermediate bowed portion, and a headed member extending between said end portions, and through an opening in one of said portions, said head being interlocked with said end portion in engagement with the outer face of said portion due to the resiliency of said clip and an 35 abutment on said member engaging the other of said portions, said clip being adapted to receive a conductor about said member between said end portions.

40 6. An electrical connector, comprising a resilient clip having substantially parallel end portions, and an intermediate bowed portion, and a headed member extending between said end portions, one of said end portions having an opening therein having a 45 wide portion and a narrow portion, said head being adapted to pass inwardly through the wide portion of said opening and normally engaging the outer face of said clip adjacent the narrow part of said opening.

50 7. An electrical connector, comprising a resilient clip having substantially parallel end portions, and an intermediate bowed portion, and a headed member having a 55 portion extending between said end portions adapted to receive a conductor, one of said end portions having an opening therein having a wide portion and a narrow portion, said head being adapted to be projected through the wide portion of said opening

and normally held in engagement with said clip adjacent the narrow part of said opening due to the resilient action of said clip, said end portion of said clip being movable relative to said other end against the resiliency thereof to align said head and the wide portion of said opening to disengage said head from the end of said clip.

70 8. An electrical connector, comprising a resilient clip having substantially parallel end portions, and an intermediate bowed portion, and a headed member extending between said end portions, one of said end portions having an opening therein having a wide portion and a narrow portion, said head being adapted to be projected through the wide portion of said opening and normally engaging said clip adjacent the narrow part of said opening, said clip being movable out of normal position to align said head and the wide portion of said opening to disengage said head from the end of said clip, said headed member having an abutment thereon between said end portions whereby a conductor may be clamped on said member between said end of said clip and said abutment.

80 9. An electrical connector, comprising a headed member and a resilient clip associated therewith having an opening having a wide portion and a narrow portion aligning with said headed member, the head on said member extending through said opening and normally engaging with the edge of said clip at said narrow portion of said opening to hold said clip in engagement with said head, said clip being bowed so that the portion of said clip having said opening exerts a pressure axially and transversely of said headed member, to hold said head in alignment with the narrow portion of said opening, said portion of said clip being axially and transversely movable against the resiliency of said bowed portion to disengage said clip from said head.

95 10. An electrical connector, comprising a headed member and a resilient clip, said clip having a portion held in fixed position relative to said headed member, an apertured portion spaced therefrom and detachably connected with the head of said headed member and resilient means normally holding said apertured portion in interlocking engagement with said head to prevent separation of said spaced clip portions and to 100 clamp a terminal between said headed member and said apertured portion of said clip.

115 11. An electrical connector, comprising a headed member and a resilient clip, said clip having a portion held in fixed position relative to said headed member, an apertured portion spaced therefrom and detachably connected with the head of said headed member and a spring connecting said portions and normally holding said apertured por-

tion in interlocking engagement with said head to prevent separation of said spaced clip portions and to clamp a terminal between said headed member and said apertured portion of said clip.

12. An electrical connector, comprising a headed member and a resilient clip, said clip having a portion held in fixed position relative to said headed member, an apertured portion detachably connected with the head

of said headed member and resilient means normally holding said apertured portion in engagement with said head, said means holding said apertured portion in such a position that said portion must be moved in two different directions to disengage the same from said head.

In witness whereof, I hereunto subscribe my name this 22nd day of May, A. D. 1922.

WALTER P. GISSKE.
